UNITED STATES PATENT OFFICE.

WAYNE W. BROWN AND JOHN B. PARSHALL, OF ST. LOUIS, MISSOURI.

DOOR-OPERATING MECHANISM.

1,187,886.

Specification of Letters Patent. Patented June 20, 1916.

Application filed September 10, 1914. Serial No. 861,047.

To all whom it may concern:

Be it known that we, WAYNE W. BROWN and JOHN B. PARSHALL, citizens of the United States, residing in the city of St. Louis and State of Missouri, have invented 5 certain new and useful Improvements in Door-Operating Mechanism, of which the following is a specification.

Our invention relates to new and useful 10 improvements in door operating mechanism and more particularly to an operator for car doors.

The primary object of the invention is the provision of a device of this character which 15 may be attached to any type of car carrying an air line.

A further object of the invention is the provision of operating mechanism which will prevent jarring of the door in opening 20 and closing.

With these and other objects in view the invention consists in the novel details of construction and arrangement of parts which will be more clearly understood from 25 the following description and drawings, in which,

Figure 1 is a view in side elevation. Fig. 2 is a longitudinal sectional view on the line B—B of Fig. 3. Fig. 3 is a top plan 30 view. Fig. 4 is an end view of the cylinder and operating mechanism. Fig. 5 is a vertical section through the cylinder on the line A—A of Fig. 1. Fig. 6 is an end view partly in section showing the inlet and exhaust valves together with the operating mechanism, and Fig. 7 is a detail of one of the valves.

In the drawings, the numeral 1 indicates a platform of a car and 2 a cylinder secured 40 under the platform. A piston 3 operates in the cylinder and has the piston rod 4 secured thereto and extending through one end of the cylinder. To the free end of the rod 4 is attached the door operating lever 5 which in turn is secured to the door, not shown in the drawings. Any connecting 45 means may be used between the lever 5 and the door as this forms no part of our invention and such connecting means might be 50 used as to open a sliding door or a swinging door.

An air line pipe 6 is shown as extending longitudinally of the car and said air pipe enters one end of the cylinder as indicated 55 at 7. Within the air pipe is a valve 8, the construction of which will be later de-

scribed in detail. A branch air pipe 9 is connected to the main line pipe 6 and enters the opposite end of the cylinder as indicated, at 10. Within the branch pipe is 60 a valve 11 the detail construction of which will be later described. At each end of the cylinder is an exhaust pipe 12 having a valve 13 therein the detail construction of which will be later described. The valve 8 65 in the inlet pipe 6 is adjacent the exhaust valve 13 in one end of the cylinder and a bar 14 connects the inlet and exhaust valves and a rod 15 extends upwardly from the bar 14 and passes through the car platform 70 where it is provided with an enlarged head 16. The valve 11 in the branch air pipe is adjacent the exhaust valve 13 in the opposite end of the cylinder and the two valves are connected by means of a bar 17 having 75 a rod 18 extending upwardly therefrom and through the platform and provided with the enlarged head 19.

The inlet and exhaust valves are each of the construction shown in Fig. 7 of the 80 drawings, comprising a casing 20 having an opening therethrough, as indicated at 21, the edges of which form a valve seat, a valve 22 and a valve stem 23 connected to the valve. The bars 14 and 17 are secured 85 to the valve stems by means of the nuts 24. A cap 25 is secured onto the valve casing and holds the bushing 26 for forming a tight joint. A spring 27 surrounds each of the stems 23 between the cap 25 and the 90 nuts 24 securing the bars 14 and 17 to the valve stems.

In the drawings we have shown the cylinder 2 as connected to the bottom of the platform by means of the flange 28 formed integral with the cylinder and the bolts 29 passing through the flange and engaging the platform. However, we do not wish to limit ourselves to this particular form of connecting means as any means might be 95 employed for attaching the cylinder to the car.

It will be seen that in constructing a door operating device as above described, we have provided such parts as may be readily attached to any car having an air system secured thereto. When the door is closed the piston 3 will be in the position within the cylinder, as shown in Fig. 2 of the drawings. When it is desired to open the door 105 the rod 18 is depressed by means of the enlarged head 19 thereby opening the valve in

the branch air line admitting air, at 10, in one end of the cylinder and at the same time opening the exhaust valve adjacent the inlet valve in the pipe. In this manner the 5 air in the forward end of the cylinder will pass out through the exhaust valve and the air will enter the opposite end of the cylinder behind the piston, forcing the same forward and opening the door. The air in the 10 forward end of the cylinder while exhausting forms a cushion for the piston thereby preventing jarring or shock when opening the door. When the rod 18 is raised by means of the spring 27 there will be air left 15 in the rear end of the cylinder where the air has previously entered. To close the door it is only necessary to engage the enlarged head 16 on the rod 15 and press downwardly thereon which will open the valve in the 20 main air line, thereby allowing the air to enter, at 7, in the opposite end of the cylinder from which it would to open the door. The opening of the inlet valve at the same time opens the exhaust valve at the end of 25 the cylinder opposite the inlet and allows the air in that end of the cylinder to exhaust as the piston is forced back to its normal position and as the air exhausts it forms a cushion to prevent jarring or shock to the 30 door.

As the valves are opened the spring 27 will be depressed and as soon as pressure is removed the springs will force the valves into closed position. In operating the 35 device, it will be found that we have provided means for simultaneously opening an inlet valve and exhaust valve whereby air is allowed to enter one end of the cylinder and exhaust through the opposite end ahead of

the piston. In this way we provide for a 40 cushioning effect and open the valves with the least possible labor.

Having fully described our invention what we claim as new and desire to secure by Letters Patent is:

1. The combination with a support of a motor, said motor comprising a cylinder, a piston operating in the cylinder, an air line entering each end of the cylinder, an inlet valve in the air line at each end of the cylinder, an exhaust valve in each end of the cylinder, a bar connecting the adjacent inlet and outlet valves, a rod passing through the support and connected to said bar for simultaneously operating said valves, and springs 55 connected to the valves and engaging the bar for normally holding the valves in raised position and acting against the pressure of the operating fluid.

2. The combination with a support, of a 60 motor, said motor comprising a cylinder, a piston operating in the cylinder, an air line entering each end of the cylinder, an inlet valve in the air line at each end of the cylinder, an exhaust valve in each end of the cylinder, means for connecting the adjacent 65 inlet and exhaust valves for simultaneously operating the same, and means for holding the valves in a raised position against the force of the exhaust air.

In testimony whereof we affix our signatures in presence of two witnesses.

WAYNE W. BROWN.
JOHN B. PARSHALL.
